BUILDING CONSTRUCTION

Filed May 19, 1926

Herman C. Blank
By Chester W. Brown
his Attorney

UNITED STATES PATENT OFFICE.

HERMAN C. BLANK, OF CHICAGO, ILLINOIS.

BUILDING CONSTRUCTION.

Application filed May 19, 1926. Serial No. 110,168.

My invention relates in general to the construction of building walls with poured concrete, and to a novel means for effecting such construction without the use of the external forms now generally employed.

The common practice in building walls with poured concrete, consists of building temporary external forms of wood and pouring the concrete into such forms. After the concrete is set sufficiently hard, the forms are removed. It will be apparent that this involves a large outlay for labor and materials, as the materials are usually damaged too much to be used again.

According to the present invention permanent members of the wall are erected, and the concrete is poured in between such members, which serve to provide a suitable form, and the whole is formed into one integral unit.

Another object is to provide a wall of the kind described which shall be fire-proof, damp-proof, and provide a suitable dead-air space for warmth and dryness.

With the above and other objects in view, which will more particularly appear in the following specification, I have employed the construction generally shown in the accompanying drawings, in which like numerals of reference indicate similar parts throughout the various views, and in which,

Figure 1 is a horizontal section of a portion of a wall showing my improved method of construction.

Figure 2 is a vertical section of a portion of a wall showing my improved construction.

In the accompanying illustrations, I have shown one style of my invention, as applied to small dwellings, garages and the like, it being apparent that the proportions may be increased as required, when it is desired to construct larger or higher buildings in this manner.

On a suitable foundation 1, formed in any of the usual ways, but preferably by poured concrete I have rested the floor joists as 15, 15 spaced in the usual manner, while between the ends, at a suitable distance from the ends, I have provided the boxing 16, forming a form for the concrete to be later poured into the space formed as hereinafter described. Upon the foundation 1 I have erected two groups of suitable channel irons, as 2 and 3, suitably spaced, and held in such spaced relation by means of the tie bars or

rods 4, 4, which may be flat pieces of metal, with holes bored at either end and adapted to be attached to the channel irons by nails or wires, as shown at 17 in Fig. 1, or may be suitable rods or wires as 4, 4, which are the preferred form, in which case the bent ends are placed in engagement with suitable holes in the channel irons, and the ends of the rods bent to form permanent connections therewith as shown in Fig. 2.

At a suitable elevation from the bottom I usually place temporarily a two inch timber as 5 between the channel irons 2 and 3, resting said timber upon temporary tie rods 4, 4 for a temporary support, and to this timber 5 I attach suitable braces as 6, 6 to hold the said channel irons in perpendicular position until a portion of the wall has been completed. When the construction of the wall has reached a point where it is convenient, this timber may be removed from the position shown, and may then be inserted at the top of the channel irons, as shown in Fig. 2. When the wall is completed, this timber is usually embedded in the concrete at the top of the wall, between the channel irons, to form a plate, to which may be attached the ceiling joists, or other portions of the frame superstructure. On the exterior side of the row of channel irons 2, I have attached suitable expanded metal lath, or wire mesh 7, which may be attached to the channel irons 2, 2 by means of the tie wires 8, 8, or any other suitable means, and may be additionally stiffened and strengthened against outward pressure of the concrete to be poured within said metal lath as hereinafter described, by means of the additional braces 9, 9, which pass about the channel irons 2, 2, and engage the metal lath at some distance from the point of contact with said channel irons 2, 2. On the interior side of the wall and of the channel irons 3, 3, I have preferably attached the metal lath, or suitable wire mesh, as 10, 10, which said metal lath is attached to said channel irons 3, 3 by means of wire ties, as 11, 11, or other suitable means, and is additionally strengthened and stiffened by means of the additional braces 12, 12, which are attached to the channel irons as shown, and engage the wire mesh or metal lath as shown at some distance from the contact between said metal lath and the said channel irons.

Between the upright rows of channel irons 2, and 3, I have provided a water-proof in-

sulating member, 13, placed adjacent the channel irons 3, 3, as shown. This insulating material is usually supported temporarily upon the tie rods 4, 4 which pass 5 there-through, and said insulating material is extended downward to about the height of the top of the floor joists as shown in Fig. 2. Portions of insulation or other suitable material may be placed between the insulating material 13, and the metal lath 10, intermediate the channel irons, if desired, as shown at 18, for the purpose of supporting the insulating material 13 against the pressure of the poured cement which is placed 10 against said insulating material, as herein-after described. Suitable wall plaster, or other plastic material is placed upon the metal lath 10 in the usual way to form the inside finish of the wall, as 14. This may 15 consist of one or more coats, as preferred by the architect. Upon the exterior of the wall upon the metal lath is placed stucco, or other suitable plastic material 19, for the outside finish of the wall, and this said finish 20 may be in one coat, or may be in several coats, as desired.

Into the space formed between the insulating member 13, and the metal lath 7 with the stucco thereon, forming the exterior of 25 the wall, is poured concrete as 23, to form a solid concrete wall, embracing said insulating material, said tie rods 4, 4, said channel irons 2, 2 and cemented to the clinches on the interior side of the metal lath 7, formed 30 by the stucco placed thereon, forming one solid wall, re-inforced by the channel irons 2, 2, the tie rods 4, 4 and the metal lath 7. As the insulating material 13 extends downward only to the top of the floor joists, this 35 leaves an opening or space formed by the boxing 16, and the concrete poured in from above as above described, fills said space between the floor joists and said boxing 16, thereby holding the joists 15, 15 in position, 40 and closing all openings, making said construction rat and vermin proof. As will be readily seen, there is formed by this construction a dead air space 24 between the insulating material 13, and the wall formed 45 by the metal lath 10 and the plaster 14 thereon, thus providing a means of resisting heat or cold, or dampness, as required.

At the corners I have preferably employed an angle iron at the outside as shown 50 at 20, Fig. 1. This angle iron may be embedded in the concrete foundation 1 as it is being erected, and when suitably plumbed, will furnish suitable lines for erecting the channel irons 2 and 3 between said corners. 55 This angle iron is suitably tied to the interior corner by the tie wires 21, 21, as shown, and the corner construction is additionally re-inforced by placing wire 22 midway between the channel irons 2 and 3 at said corners, to re-inforce said corner and prevent 60

cracking or breaking of the concrete wall at the corners.

Suitable openings are left for the windows and doors, which may be of factory make, as usual. If it is desired, the lintels 10 for doors and windows may be of angle irons, or I-beams, as in brick, or tile construction as at present employed to make the wall fire-proof.

As my construction eliminates all wooden forms, and the labor and expense of the materials, it will be apparent that it is much more economical than the former methods employed. Again, the material and parts placed in position, form a permanent part of the completed wall, and assist in reinforcing said wall, and making it stronger and less liable to crack or be damaged than would be the case with a wall not so reinforced. It will be further seen, that my construction contemplates a completely finished wall, when the work is finished, with no parts to be altered, changed or removed. It is contemplated in erecting my said concrete wall, that after the channel irons, and wire lath and insulating material is in place, the stucco masons on the outside, and the plasterers on the inside shall start a course around the wall, and when these courses are sufficiently set, the concrete workers begin pouring the concrete to form a like course, and follow the direction of the masons around the building. When the masons and plasterers have completed their first course, the concrete workers will be out of their way, and they can apply a second course, and thus the workers follow one another around the building, laying course on course, until the wall is fully completed.

Having thus described my invention, what I claim and desire to secure by Letters Patent, is the following:—

1. A form for concrete wall construction comprising upright channel irons, metal lath attached to said channel irons, plastic material upon said metal lath, insulating material between the courses of channel iron adjacent the inner course, concrete poured into the space formed between the metal lath on the exterior of said wall, and the insulating material, and a top plate of a width equal to the space between the channel irons and adapted to be guided by the same in the construction of the wall and embedded in the plastic material at the top of the wall between the said inner and outer channel irons.

2. In building wall construction, the combination of a foundation, inner and outer groups of uprights spaced in parallel relation and mounted upon the foundation floor joists supported upon the foundation at the inner group of uprights, metal lath on exterior and interior sides of said uprights, an insulating material mounted on the

inner group of uprights at the inner face thereof in spaced relation with the adjacent metal lath and spaced from the foundation to provide an opening to permit concrete to flow between the joists, and vertical boxings arranged between the joists and extending upwardly from the foundation and confining over the foundation the plastic material flowing between the said joists.

3. A wall forming construction comprising spaced concrete, retaining elements consisting of insulating material on one side, a

metal lath covered with plastic material on the other, said elements being supported by 15 suitable upright channel irons and approximately V-shaped ties fitting against the channel irons at the inner faces thereof and having diverging side portions extending to said metal lath to hold the said elements 20 firmly against the outer faces of the channel irons and forming permanent parts of the complete wall.

In testimony whereof, I have hereunto affixed my signature, as required.

HERMAN C. BLANK.
